In a solvent extraction system utilizing a counter-current extraction column and an extractive distillation stripper for recovery of C₆—C₈ aromatic hydrocarbons, the feed is divided into light and heavy fractions containing, respectively, C₆—C₇ and C₈ aromatics. The light fraction is introduced to the extraction column at an intermediate level along with the overhead stream from the stripper column, while the heavy fraction is introduced to the extraction column at a lower level. This procedure avoids loss of C₈ aromatic components to the raffinate.

SOLVENT EXTRACTION OF C₆—C₈ AROMATIC HYDROCARBONS

BACKGROUND OF THE INVENTION

This invention relates to the processing of gasoline or naphtha stocks containing aromatic hydrocarbons of the C₆—C₈ range with the aid of an aromatic-selective solvent. The invention constitutes a variation from processing procedures heretofore proposed, whereby better recovery of the C₈ aromatic constituents of the feed is achieved.

The selective extraction of aromatics from naphthas is practiced widely. The Udex process utilizing a glycol type solvent has wide commercial use for extracting aromatics of the C₆—C₈ range. This process is described in *Hydrocarbon Processing*, Sept. 1970, p. 248. In conventional practice of this process the hydrocarbon feed stream containing all of the C₆—C₈ aromatics is introduced at an intermediate level into a countercurrent extraction column in which the solvent phase flows downwardly. The raffinate and extract phases are removed from the top and bottom of the column, respectively. The extract phases are sent to an extractive distillation stripper column from which saturated hydrocarbons together with some aromatic material is stripped overhead. This overhead material is returned to a lower part of the extraction column as reflux. A mixture of high aromaticity containing the C₆—C₈ aromatics is removed at an intermediate level from the stripper column, while the solvent is recovered from the bottom and recycled to the top of the extraction column.

While the foregoing processing procedure results in high purity aromatic products and the recovery of substantially all of the benzene and toluene from the feed, there is a tendency for C₈ aromatics to be lost to the raffinate. This is due to the fact that these are the aromatic feed components which are least soluble in the selective solvent. Also the stripper overhead used as reflux in the extraction column generally contains a substantial content of naphthenes, typically of the order of 20–40 percent by volume, which have a tendency to displace C₈ aromatics from the solvent phase and cause these components to appear in the raffinate. As a result incomplete recovery of the C₈ aromatics usually is experienced in conventional operation.

Variations have been proposed in the processing scheme wherein the feed is first fractionated into light and heavy fractions and these fractions are introduced at different levels into the extraction column or into separate columns operated in an integrated fashion. Examples of such proposals appear in the following U.S. Pat. Nos.: 3,037,062, C. G. Gerhold, issued May 29, 1962; 3,422,163, G. F. Asselin, issued Jan. 14, 1969; 3,468,792 and 3,468,793, K.D. Uitti, issued Sept. 23, 1969.

In aforesaid U.S. Pat. No. 3,422,163 the feed material is divided into a light fraction and a heavy fraction, the light fraction is fed to the extraction column near the bottom along with overhead material obtained from the stripper column, and the heavy fraction is introduced to the extraction column at an intermediate level. This scheme has the same drawback as mentioned above for the more conventional procedure, namely, the tendency to lose C₈ aromatics to the raffinate due to their displacement from the solvent phase in the lower part of the extraction column.

SUMMARY OF THE INVENTION

The present invention provides a different way of operating an extraction system comprising a countercurrent extraction column and an extractive distillation stripper column so that loss of C₈ aromatic components to the raffinate is avoided.

The procedure according to the invention involves dividing the feed material into a light naphtha fraction 10 containing C₆—C₇ aromatic material and a heavy naphtha fraction containing C₈ aromatics. The light fraction is introduced to the extraction column at an intermediate level, and the heavy fraction is introduced thereto at a lower level. In one embodiment the heavy fraction 15 is introduced adjacent the bottom of the column to function as reflux; while in another embodiment it enters the column substantially above the bottom and a portion of the C₆—C₈ aromatic product is recycled and introduced adjacent the bottom to serve as reflux. The extract phase from the bottom of the extraction column is passed into the top of the stripper column wherein substantially all non-aromatic hydrocarbons are stripped out as overhead. This stripper overhead stream is recycled back to the extraction column, being introduced therein at the same or about the same level of introduction as the light naphtha fraction. The C₆—C₈ aromatic product of high purity is withdrawn as a sidestream from the stripper column, while solvent is removed from the bottom and recycled back to the top 30 of the extraction column.

BRIEF DESCRIPTION OF THE DRAWINGS

FIG. 1 is a schematic flowsheet illustrating a conventional manner of recovering the aromatic components from naphthas, which figure is included for purpose of comparison.

FIGS. 2 and 3 are schematic flowsheets illustrating the two different embodiments of the invention referred to above.

DESCRIPTION

The invention can be utilized for the processing of any naphtha or gasoline stocks containing aromatics of the C₆—C₈ or C₇—C₈ boiling range, including straight run fractions, reformates, catalytic gasolines and the like. The process is particularly useful for recovering benzene, toluene and xylenes from stocks of relatively high aromaticity, such as catalytic reformates boiling typically in the range of 80°–300°F.

The conventional manner of extracting such stocks is illustrated in FIG. 1. Feed naphtha containing the C₆, C₇ and C₈ aromatics is introduced through line 10 to countercurrent extractor 11 at an intermediate level and flows upwardly countercurrent to the aromatic-selective solvent which is fed into the column near the top through line 12. The raffinate stream leaves the top of the column via line 13, while the extract phase passes from the bottom through line 14. The extract phase is fed into the upper part of an extractive distillation stripper 15 wherein non-aromatic components are stripped out leaving the column as overhead through line 16. This overhead product, which also contains a substantial proportion of the lighter aromatic components, is recycled through line 16 and introduced as reflux into the lower part of extractor 11. In stripper 15 the C₆—C₈ aromatic material is also removed, being obtained as a sidestream product through line 17. The

solvent recovered from the bottom of stripper 15 is returned through line 12 to the extraction column.

In processing catalytic reformate of 80°-295°F. boiling range, for example, by the conventional procedure of FIG. 1, the overhead from stripper 16 typically will have a composition by volume as follows:

olefins - 5-15%
aromatics (mostly C₆-C₇) - 30-60%
naphthenes (mostly methylcyclopentane) - 20-40%
paraffins - 10-20%

When this material is returned to the extraction column as reflux through line 16, the naphthene components (mainly methylcyclopentane) have considerable tendency to displace the least soluble aromatic components from the solvent phase. These components are those of highest molecular weight, i.e. the C₈ aromatics. A substantial loss of C₈ aromatics to the raffinate phase which leaves the top of extractor 11 is therefore generally experienced.

FIG. 2 illustrates one embodiment of the present invention which provides a better recovery of the C₈ aromatic components than is normally experienced in the conventional operation. This embodiment is particularly useful in processing catalytic reformates typically boiling in the range of 80°-295°F. The feed naphtha is first sent to a fractionator 20, as indicated by line 21, from which a light naphtha fraction containing aromatics of the C₆-C₇ range is taken overhead via line 22 and a heavy naphtha cut containing the C₈ aromatics is removed as bottoms through line 23. Typically the light and heavy fractions separated from the reformate will boil in the ranges of 80°-270°F. and 270°-295°F., respectively, the heavy fraction will usually have a C₈ aromatic content of 80 percent or more.

As indicated in FIG. 2 these light and heavy fractions are introduced into extractor 24 at different levels, with the light fraction entering near the middle and the C₈ aromatic fraction being introduced through line 23 near the bottom as reflux for the countercurrent extraction operation. The aromatic-selective solvent enters near the top of column 24 through line 25 and flows downwardly countercurrent to the hydrocarbon phase. Raffinate is obtained from the top through line 19. Solvents useful for this type of extraction are well known and have been described in numerous patents; see, for example the patents cited hereinabove. Solvents of the glycol type, such as diethylene glycol, di-propylene glycol, and various polyethylene or polypropylene glycols generally are preferred, but any other known or suitable aromatic-selective solvents can be used.

The extract phase from extractor 24 is transferred from the bottom through line 26 to the top of stripper 27. The latter functions in a manner similar to the stripper of FIG. 1, except that substantially less material need be stripped overhead and this overhead material generally will contain a lower proportion of saturated hydrocarbons than in the conventional process. Again the C₆-C₈ aromatic extract product is removed as a sidestream through line 28. The overhead stream, instead of being used as reflux as in the conventional process, is fed to the extraction column 24 at the same level or about the same level as where the light naphtha fraction enters. Thus, as shown in FIG. 2, the overhead stream is sent through line 29 to line 22 where it joins the light naphtha feed before entering the extractor.

This introduction of the stripper overhead recycle to extractor 24 at an intermediate level along with the light naphtha feed instead of near the bottom results in an increase in the yield of C₈ aromatics in the aromatic extract. This beneficial result comes about because, in the FIG. 2 process, the naphthenic components of the stripper overhead do not have the opportunity to displace the higher aromatic components from the extract phase. Comparative material balance data given in the accompanying tables illustrate the benefit to be derived by operating in the manner of this invention.

FIG. 3 illustrates a modification of the process of FIG. 2. Most of the system of FIG. 3 is the same as that of FIG. 2 and the corresponding parts are identified by the same numerals. The difference resides in the material introduced into extractor 24 near the bottom as reflux. In the process of FIG. 3, a portion of the C₆-C₈ aromatic extract from line 28 is recycled through line 30 to extractor 24 and enters as reflux near the bottom, while the heavy naphtha feed is introduced through line 23a substantially above the bottom but below the level of introduction of the light naphtha feed from line 22. This modification in procedure is particularly advantageous when the heavy naphtha fraction is not highly aromatic, as when straight run fractions are being processed. In such cases the use of the heavy naphtha fraction as reflux for the extraction, as per FIG. 2, tends to permit non-aromatic components to appear in the C₆-C₈ aromatic product. Thus, while a high yield of the aromatics is obtained, the purity of the product may not be as high as desired. Use of the procedure of FIG. 3 allows both high yield and high purity to be secured.

Tables I, II and III give typical material balance data (based on 100 volumes of feed per hour) for the various streams of FIGS. 1, 2 and 3, respectively, when processing a catalytic reformate boiling in the range of 80°-295°F. obtained from a reforming process employing a conventional platinum-containing catalyst. For illustrating the embodiments of FIGS. 2 and 3 it is assumed that the reformate feed to the two processes are of slightly different compositions so that the heavy naphtha fraction in the FIG. 3 process has a somewhat higher content of saturated hydrocarbons (about 15 percent) than in the FIG. 2 process (about 10 percent).

TABLE I
Material Balance for Reformate Processing per Fig. 1
(Basis: 100 vols. feed/hr.)

Component	Reformate feed (line 10)	Raffinate (line 13)	C ₆ -C ₈ Aromatic product (line 17)	Stripper recycle (line 16)
olefins	1.0	1.0	—	10
benzene	6.5	—	6.5	40
toluene	20.2	1.0	19.2	5
C ₆ aromatics	10.3	2.1	8.2	—
C ₈ aromatics	1.0	0.5	0.5	—
C ₆ naphthenes	2.9	2.9	—	30
C ₅ -C ₆ paraffins	17.6	17.6	—	15
other saturates	40.5	40.5	—	—
Total vol./hr. =	100	65.6	34.4	100

Comparison of the data in Table I with that of Tables II and III shows that in either embodiment of the invention there is less loss of C₈ aromatics to the raffinate and a correspondingly higher recovery thereof in the C₆-C₈ aromatic product. It also shows that a substantial reduction is effected in the amount of material that needs to be taken overhead from the stripper.

While the embodiments of the invention have been described above for processing feeds of the C₆—C₈ aromatic range, they are also applicable to the processing of narrower boiling feeds of the C₇—C₈ aromatic range. In such case the feed is fractionated into a light naphtha containing toluene and a heavy naphtha containing C₈ aromatics, and the fractions are processed in the same manner as described.

The invention claimed is:

1. Process for extracting C₆—C₈ aromatic hydrocarbons from naphtha stocks containing the same which comprises:

- a. passing an aromatic-selective solvent downwardly through a countercurrent extraction column;
- b. feeding a light naphtha fraction containing principally aromatic hydrocarbon of the C₆—C₇ range and saturates into said column at an intermediate

- 35 f. recycling the stripper overhead stream to said extraction column and introducing same therein at about the level of introduction in step (b);
- g. recycling solvent from the bottom of said stripper column for reuse as specified in step (a);
- h. and withdrawing from an intermediate level of said stripper column a C₆—C₈ aromatic product stream of high purity.

40 2. Process according to claim 1 wherein the level of introduction of said heavy naphtha fraction in step (b) is near the bottom of said extraction column, whereby the heavy naphtha fraction serves as reflux.

45 3. Process according to claim 1 wherein the level of introduction of said heavy naphtha fraction in step (b) is substantially above the bottom of said extraction column and a portion of said C₆—C₈ aromatic product stream is recycled to said extraction column and introduced therein near the bottom to serve as reflux.
